UNITED STATES PATENT OFFICE.

RUBAN CANTOR, OF BROOKLYN, NEW YORK, ASSIGNOR TO ROYAL GLASS WORKS, OF BROOKLYN, NEW YORK, A FIRM.

UNLOADING DEVICE.

Application filed November 15, 1926. Serial No. 148,428.

My invention relates to a new and improved device for loading and unloading vehicles.

One of the objects of my invention is to provide a simple, safe and efficient skid device for unloading heavy, fragile objects from trucks, such as large sheets of plate-glass and the like.

Another object of my invention is to provide a device which will be extremely light and compact and can be readily assembled and taken apart as far as is necessary for convenient transportation.

Other objects of my invention will be set forth in the following description and drawings which illustrate a preferred embodiment thereof, it being noted that the above statements of the objects of my invention is intended to generally illustrate the same and not to limit it in any manner.

Fig. 1 is a side view showing the device in the inoperative position and connected to the side of a truck.

Fig. 2 is a detail view of a part of the device illustrated in Fig. 1, showing the skid in operative position.

Fig. 3 is a plan view showing the skid.

Fig. 4 is a detail view similar to Fig. 3.

Fig. 5 shows the underside of the device illustrated in Fig. 4.

Fig. 6 is a section on the line 6—6 of Fig. 4.

Heretofore it has required a large amount of labor to carefully unload large sheets of plate-glass from trucks because the article was heavy and fragile and had to be handled very carefully.

According to my invention a very smooth and efficient skid device is provided whereby one or two laborers can efficiently unload a very large and heavy sheet of plate-glass from a truck.

The truck T may be of any ordinary type and it is provided with uprights of the usual form.

The sheet of plate-glass is enclosed in a box B of the ordinary type.

The rear of the floor 10 of the truck is provided with a series of openings 11. The skid is made of a series of light wooden members 12 secured to each other so as to constitute a complete skid or an element thereof. As shown more fully in Fig. 5, the boards 12 are secured in pairs, or in any other convenient number, by means of metal

connecting members 15 which are secured to the boards 12 by means of rivets 16. The boards 12 and the connecting members 15 are provided with common openings 17 into which uprights 24 may fit.

As shown in Fig. 3 a skid may consist of four boards 12 so that the uprights 24 can be located in the opening 17 at varying distances from each other. This makes it possible to operate the device with boxes B of different widths so that the boxes B may be allowed to move downwardly upon the skid without any danger of their tipping over on one side. Hence the only labor which is necessary is that required to cause the boxes B to slowly descend.

The boards 12 are provided with hooks 13 secured thereto by means of rivets 14 and said hooks 13 engage the openings 11 of the floor 10 of the truck. The hooks 13 are arranged in groups of three. The end members of each group are each connected to a single board 12 and the intermediate member 13 of each group has its rear curved so that it is connected to two adjacent boards 12. This produces a strong but very light structure.

As shown in Figs. 4 and 5 the hooks 13 are provided with curved front portions 13a.

The truck T is provided with bars 20 connected thereto by means of hinges 21. A skid member can be placed upon the outside of the uprights of a truck and the skid member can be held between said uprights and the bars 20. When the bars 20 are turned upwardly they are held in position by means of members 23 which pass through eyes 22 connected to the undersides of the bars 20. Front bars 21' are provided which are similar in all respects to the rear bars 20, save that the front bars 21' are curved.

Each connected group of bars 12, which may be considered as forming a skid element or unit, is provided with an end metal member 18 connected to the end board 12 by means of a rivet 19. Hence a number of skid units can be conveniently assembled as shown in Fig. 6, because the end board 12 of one unit can rest upon the projecting ledge member 18 of the adjacent unit.

It is obvious that the device is very simple, light and compact and can be used very conveniently.

The boards 12 can be made of any ordinary wood because the openings 17 therein

are reenforced by the corresponding openings in the metal connected members 15. This enables the use of wood for making the main portion of the device so that the skid member is light, cheap and strong.

I have shown a preferred embodiment of my invention, but it is clear that numerous changes and omissions could be made without departing from its spirit.

10 I claim:-

1. A skid member for unloading heavy, fragile objects from trucks comprising a plurality of boards connected at their undersides by means of intermediate connecting members, the said boards and the said connecting members having common openings

into which uprights may be fitted at varying lateral distances from each other.

2. A skid element including two adjacent boards, the said boards being connected to 20 each other by an intermediate metal connecting member, the said connecting member and the said boards having common openings, the said boards having three hook members connected to the ends thereof, the two outside hook members being respectively connected to each of said boards, and the intermediate hook member having its shank connected to both of said boards. 25

In testimony wherof I affix my signature.

RUBAN CANTOR.
